(57) CLAIM

I claim the ornamental design for gaming desk with X shaped legs, as shown and described.

DESCRIPTION

The patent or application file contains at least one drawing executed in color. Copies of this patent or patent application publication with color drawing(s) will be provided by the office upon request and payment of the necessary fee.

FIG. 1 is a perspective view of gaming desk with X shaped legs, showing my new design;

FIG. 2 is a front perspective view thereof;

FIG. 3 is a bottom perspective view thereof;

FIG. 4 is a top perspective view thereof;

FIG. 5 is a rear perspective view thereof;

FIG. 6 is a left side view thereof; and,

FIG. 7 is a right side view thereof.
